UNITED STATES PATENT OFFICE.

THOMAS C. NICHOLSON, OF MEMPHIS, TENNESSEE.

DOOR-FASTENER.

No. 890,441.

Specification of Letters Patent.

Patented June 9, 1908.

Application filed November 19, 1907. Serial No. 402,890.

To all whom it may concern:

Be it known that I, THOMAS C. NICHOLSON, a citizen of the United States, residing at Memphis, in the county of Shelby and State of Tennessee, have invented new and useful Improvements in Door-Fasteners, of which the following is a specification.

This invention is an improved door fastener, especially adapted for use by travelers for fastening doors so that they can not be opened from the outside, the object of the invention being to provide a simple, light, cheap and exceedingly compact door fastener which may be carried readily in a pocket or other small receptacle, and which may be readily applied to a door for the purpose of fastening the door, without the necessity of employing tools, and which may also be readily detached from the door, and the said invention consists in the construction, combination and arrangement of devices.

In the accompanying drawings, Figure 1 is a plan of a door fastener constructed in accordance with my invention, showing the same applied, a portion of the door and of the frame being indicated in section. Fig. 2 is a perspective view of my improved door fastener showing the same in extended position. Fig. 3 is a similar view showing the same in folded position and compactly disposed. Fig. 4 is a plan view of the bolt.

My improved door fastener comprises a guide and stop frame, combined with a bolt which is longitudinally movable in said frame and is also adapted to be folded longitudinally to compactly dispose the bolt and enable the fastener to be readily carried in a pocket or other small receptacle and effect a compact disposition of the fastener.

In the embodiment of my invention here shown, the stop and guide frame 1 is rectangular in cross-section, is provided with a longitudinal guide groove which is coextensive in length therewith and is also nearly coextensive in width therewith, and on one side of the said frame is a longitudinal slot 2 which extends from end to end thereof. At one end of said frame which I will term the inner end thereof is a flange 3 which extends around the sides thereof and when the fastener is in use is adapted to bear against the inner side of the door and the proximate portion of one side of the door jamb or frame as shown in Fig. 1. In one side of the said frame at a point opposite the groove 2 is a set screw 4.

The bolt 5 which is slidable longitudinally in the frame comprises an inner section 6 and an outer section 7 hinged together as at 8, the hinged connections between said sections projecting from one side thereof and disposed in the slot 2 which serves to clear the same. The inner end of the section 6 is provided with a wedge-shaped head 9 which is adapted to be inserted in the latch opening of a strike plate, the shoulder 10 thereof engaging one wall of the opening as shown in Fig. 1, in which the door is indicated at *a*, and the strike plate is indicated at *b*, the lock not being shown. The section 6 is reduced as at 10^a to permit the application of the head 9. When the bolt is drawn in one direction in the frame, the shoulder 10 thereof comes in contact with the stop end of the frame and the outer section 7 of the bolt may be then folded 15 on the frame over the slot 2, as shown in Fig. 3, thereby effecting an exceedingly compact disposition of the fastener and enabling the same to be readily placed in a pocket or other small receptacle.

In the operation of my improved door fastener, the bolt is first extended and is moved longitudinally in the frame to enable the head 9 thereof to be inserted in the latch opening of a strike plate so that when the door is closed the removal of the fastener is impossible. The frame is then moved on the said extended bolt to cause its stop end 3 to bear against the door and the jamb or frame, and the set screw is then caused to firmly engage the outer section 7 of the bolt so as to lock the frame firmly on the bolt and enable the frame to resist pressure applied to the door from the outer side thereof, and hence counteract any attempt to open the door 95 from the outside. The sections are roughened as at 4^a to permit the firm engagement of the set screw therewith.

It will be understood that in order to release the fastener from the door it is only necessary to first disengage the set screw 4 from the bolt and then disengage the frame from the bolt, whereupon the door may be readily opened, after which the head of the bolt may be readily disengaged from the 105 strike plate. It is to be understood that the fastener can be used on a door provided with a rim lock.

Having thus fully described the invention, what is claimed as new is:

1. A door fastener of the class described comprising a stop and guide frame open at its

ends and a hinged bolt slidable longitudinally in said frame, said bolt being provided at one end with a head for the purpose set forth, said head being adapted to engage one end of the guide and stop frame when said bolt is drawn in one direction, one section of the bolt when said head is thus in contact with one end of the stop and guide frame being foldable against one side of said stop and guide frame.

2. A door fastener of the class described comprising a stop and guide frame open at its ends and a hinged bolt slidable longitudinally in said frame, said bolt being provided at one end with a head for the purpose set forth,

20 said head being adapted to engage one end of the guide and stop frame when said bolt is drawn in one direction, one section of the bolt when said head is thus in contact with one end of the stop and guide frame being foldable against one side of said stop and guide frame, and a set screw in one side of said stop and guide frame to engage said bolt and secure the same against longitudinal movement.

25 In testimony whereof I affix my signature in presence of two witnesses.

THOMAS C. NICHOLSON.
